FIG. 1

FIG. 2

FIG. 3

FIG. 4

FIG. 5

FIG. 6

FIG. 7

FIG. 8

FIGURE 1 is a view in perspective view of a lavatory embodying my new design;

FIGURE 2 is a top plan view of the same;

FIGURE 3 is an end view of the same;

FIGURE 4 is a front view of the same;

FIGURE 5 is a perspective view of a modified form of the lavatory shown in FIGURES 1 to 4; and

FIGURES 6, 7 and 8 are top plan, end elevation and front elevation, respectively, of the lavatory shown in FIGURE 5.

The dominant features of my design reside in the portions shown in full lines.

The characteristic feature of my design for a lavatory resides in the upstanding portion of the ledge for supporting the fittings at the rear thereof, being offset from the center, as shown.

This application is a continuation-in-part of my application Serial No. D. 64,360 filed March 17, 1961 now abandoned.

I claim:

The ornamental design for a lavatory, as shown and described.
